CLAIM

The ornamental design for a French dip manicure powder case, as shown and described.

DESCRIPTION

FIG. 1 is a perspective view of a French dip manicure powder case showing our new design;

FIG. 2 is top view thereof;

FIG. 3 is a bottom view thereof;

FIG. 4 is a right side view thereof;

FIG. 5 is a left side view thereof;

FIG. 6 is a back view thereof;

FIG. 7 is a front view thereof;

FIG. 8 is an exploded perspective view of the French dip manicure powder case of FIG. 1 showing the lid of the case separated from the base of the case;

FIG. 9 is a perspective view of the French dip manicure powder case of FIG. 1 shown with the lid removed for ease of illustration;

FIG. 10 is a top plan view thereof;

FIG. 11 is a bottom plan view thereof;

FIG. 12 is a right side view thereof;

FIG. 13 is a left side view thereof;

FIG. 14 is a back view thereof; and,

FIG. 15 is a front view thereof.

The broken lines depict a boundary which forms no part of the claimed design. The unshaded area within the broken lines forms no part of the claimed design.

1 Claim, 5 Drawing Sheets
